BOTTLE FOR LIQUIDS

William F. Wood, 109 La Paloma Ave., Alhambra, Calif.

Filed Feb. 9, 1965, Ser. No. 83,749

Term of patent 14 years

(Cl. D58—6)

FIG. 1 is a side elevation of a bottle for liquids showing my new design;

FIG. 2 is a top plan view thereof;

FIG. 3 is an end elevation thereof; and

FIG. 4 is a plan section taken along line 4—4 of FIG. 1.

The side not shown is a mirror image of the side shown and the end not shown is the same in appearance as the end shown.

I claim:

The ornamental design for a bottle for liquids, as shown and described.
